UNITED STATES PATENT OFFICE.

AUGUST B. DRAUTZ, OF STUTTGART, WÜRTEMBERG, GERMANY.

SHOE-FASTENING.

SPECIFICATION forming part of Letters Patent No. 425,567, dated April 15, 1890.

Application filed August 20, 1889. Serial No. 321,437. (No model.)

To all whom it may concern:

Be it known that I, AUGUST B. DRAUTZ, a citizen of the Kingdom of Würtemberg, Germany, residing at Stuttgart, in Würtemberg, have invented a new and useful Improvement 5 in Fastenings for Shoes, Gloves, &c., of which the following is a specification.

The object of my invention is to form a fastener for shoes, gloves, and slippers by means of which these articles of clothing may be rapidly fastened at one pull and undone (opened) with equal facility, and which has the further quality of adapting itself to any form of the body to be covered.

15 In the annexed drawings this fastener is shown as attached to a shoe, and—

Figure 1 represents a front elevation of the fastener; Fig. 2, a side elevation of the fastener secured to a shoe; and Figs. 3 to 7 show 20 details.

Along the edges of the flaps of the shoe S, which are to be fastened together, are secured spiral springs s, or other suitable liners are sewed into the leather, by means of which 25 very elastic, although resisting, ridges A' and A² are formed, which readily adapt themselves to any form of the portion of the body to be covered. Around these two ridges A' and A² pass clamps b b² b³, &c., which are so secured to two strings a' and a² that on the 30 string a', which is to effect the fastening, Fig. 3, the clamps b' to b⁵ are fastened at certain fixed intervals, while the other string a², which is to be used in loosening the fastening, passes freely through holes in the clamps b' to b⁵, and is secured only to the end clamp b⁵. At the other ends of the strings a' and a² are the buttons K' and K², respectively, which are used to adjust and secure the 40 fastening. At the lower ends of the two ridges A' and A² there is an eye O, through

which the string a² passes. When the fastening is secured, the button K² is against this eye and prevents a further rise of the clamps b' to b⁵.

The fastening is performed by pulling upon string a', and raising the clamps until the button K² is against the eye o.

In order to prevent the loosening of the fastening, the upper end of the closing-string a' is secured around two heads on the ends of the spiral springs s, and is then passed through a slit in the end clamp b⁵, so that the button k' lies against the slit.

The unfastening is performed by grasping 55 the button K² and pulling on string a², by means of which the clamp b⁵ is pulled upon b⁴, b³ upon b³, &c., all the clamps being thus pulled back.

I claim—

1. A fastening device for shoes, gloves, and the like, consisting of the flaps provided with spiral springs at their edges, and a series of sliding clamps, and means, substantially as described, for operating said clamps, all in 65 combination, substantially as described.

2. In a fastening device for shoes, gloves, and the like, the fastening-string having secured to it at intervals the fastening-clamps, in combination with an unfastening-string 70 attached to the uppermost clamp and passing loosely through the other fastening-clamps, in combination with the spiral springs secured to the edges of the flaps, substantially as described.

In testimony whereof I have signed this specification in the presence of two subscribing witnesses.

AUGUST B. DRAUTZ.
